LIQUID FUEL BURNER HAVING SURFACE COMBUSTION PILOT

Fred B. Aubert, Detroit, Mich.

Application September 18, 1947, Serial No. 774,826

5 Claims. (Cl. 158—91)

1

This invention relates to new and useful improvements in liquid fuel burners of the gravity fed type.

One of the objects of this invention is to provide a new and improved liquid fuel burner of the surface combustion type.

Another object is to provide a burner which is particularly adapted for use as a constantly burning pilot.

Another object is to provide a pilot which will operate efficiently upon a very low consumption of fuel.

Another object is to provide a liquid fuel burner with an improved pilot for pilot operation and an improved means for vaporization of fuel for normal operation.

Other objects will be apparent from time to time throughout the specification and claims as hereinafter related.

In the accompanying drawings, to be taken as a part of the specification, there are clearly and fully illustrated two preferred embodiments of the invention, in which drawings:

Figure 1 is a view in vertical cross-section of a burner pot having an enclosed pilot and diagrammatically showing a fuel valve and conduit for supplying fuel to the pilot.

Fig. 2 is a plan view of the burner pot and pilot shown in Fig. 1, and

Fig. 3 is a view in vertical cross-section of a burner pot having a fuel well with a pilot therein and a fuel vaporization member and diagrammatically showing a fuel valve and conduit for supplying fuel to the well.

Referring to the drawings by characters of reference in the form of the invention shown in Fig. 1 there is a burner 1 having a pot 2. The pot 2 has a solid bottom portion 3 and a perforated upper portion 4 having a plurality of air inlet holes 5. Covering approximately a quadrant of the bottom portion 3 and seating along its upper periphery along the upper portion 4 is a wall or cover member 6 enclosing a pilot chamber 7. The wall member 6 is secured to the upper portion 4 of the pot 2 by bolt members 8 extending through ear portions 9. The bottom portion 3 of the pot 2 has an inlet port 10 opening into the pilot chamber 7. The inlet port 10 is operable to receive a fuel conduit 11 which supplies fuel by gravity from a fuel valve 12. The pilot chamber 7 is loosely filled with elongated strips 13 of small cross section of a high melting point oxidation resisting metal. These elongated strips of metal may be a fine wire or fine metal turnings or the like. When

2

the liquid fuel is fed to the pilot chamber 7 and ignited the metal strips are heated to incandescence and thereafter maintain an incandescent surface combustion for operation as a burner pilot. It was found experimentally that a very fine steel wire such as steel wool gave the best surface combustion but would oxidize too rapidly. Highly heat conductive metals such as copper or aluminum tend to melt. From further experimental information it was found that the metal must have a high melting point and be oxidation resistant. A high temperature stainless steel such as A. I. S. I. #347 or #309 or the like meets both the requirements of high melting point and of oxidation resistance. When a small pilot flow of fuel is fed to the chamber 7 an incandescent surface combustion is maintained and the temperature of the chamber 7 is raised to a point that a continuous vaporization of fuel may be had in the chamber. As additional amounts of fuel are supplied to the chamber 7 for normal burner operation the fuel is vaporized and ignited for combustion as a flame. With a slight excess of fuel over that required for pilot operation a small flame 14 as is shown in Fig. 1 will emerge from the pilot chamber 7 through the opening 14a. As more fuel is supplied, the flame 14 will grow in size until large amounts of fuel vapors are emerging from the chamber 7 and mixing with the combustion air in the upper portion 4 of the pot 2 and substantially all combustion is taking place at that point. When the fuel supply is cut down, as for pilot operation, the amount of vaporized fuel supporting the flame 14 is correspondingly diminished so that the flame will diminish in size. As the amount of fuel vapor supporting the flame 14 is diminished to a point where all of the fuel being supplied is sufficient to maintain only a surface combustion on the metal strips 13, the flame 14 will diminish in size until it extinguishes itself within the chamber 7 and the metal strips 13 will continue to glow and maintain a continuous incandescent surface combustion.

In the form of the invention shown in Fig. 3 there is a liquid fuel burner 15 having a combustion pot 16. The pot 16 has a bottom portion 17 and a perforated side wall portion 18 which has a plurality of air inlet apertures 19. The pot 16 has a recessed fuel well portion 20 which opens upwardly through an aperture 21 in the bottom wall portion 17. The fuel well portion 20 has a bottom wall 22 and a side wall 23 which has one or more air inlet apertures 24 therein. There is a fuel inlet aperture 25 in the

3

lower portion of the fuel well wall 23 which is operable to receive a fuel supply conduit 26 which provides gravity flow of fuel from a fuel control valve 21. Positioned in the fuel well portion 20 and extending upwardly through the aperture 21 into the upper portion or zone of combustion of the pot 16 is a rod member 28 of a highly heat conductive metal such as copper. The rod member 28 is operable upon heating to vaporize the fuel supplied to the fuel well portion 20. There is an annular disc member 29 carried by a shoulder portion 30 of the rod member 28 which covers and partially closes the aperture 21 leaving only the annular space between the disc member 29 and the pot bottom wall 17 for the supply of fuel vapors from the fuel well portion 20 to the pot 16. The annular space between the fuel well wall 23 and the rod member 28 is loosely filled up to the disc member 29 with elongated strips 31 of small cross section of a high melting point oxidation-resistant metal such as fine turnings of one of the heat-resistant stainless steels heretofore mentioned.

In this form of the invention, as in that shown in Fig. 1, when a small pilot flow of fuel, which may be as small as 1 cc. per minute, is fed to the fuel well portion 20 and ignited the stainless steel turnings are heated to incandescence and thereafter maintain an incandescent surface combustion thereon. When an excess of fuel above that required for pilot combustion is supplied a flame 32 will emerge from the annular space below the disc member 29 and normal combustion will take place in the burner pot 16. During normal combustion in the pot 16 the rod member 28 is heated and this heat is conducted to the portion of the rod 28 in the fuel well portion 20 where it is utilized to vaporize the fuel supplied thereto. It should be noted that the fuel well air inlet 24 is positioned above the maximum level of liquid fuel in the fuel well portion 20. The disc member 29 is heated by conduction from the rod member 28 and functions to vaporize liquid fuel particles which may be entrained with the fuel vapors emerging from the annular space therebelow. When increasing amounts of fuel are supplied to the fuel well portion 20 the fuel is vaporized by the heated rod member 28 and disc member 29 and ignited by the glowing turnings 31 for combustion in pot 16. As was described for the form of the invention shown in Fig. 1, when the supply of fuel to the fuel well portion 20 is decreased the size of the flame 32 decreases until it extinguishes itself in the fuel well portion 20, the combustion continuing as surface combustion on the glowing turnings 31 which function as a continuously burning pilot to subsequently reignite the fuel for another cycle of normal burner operation.

It should be noted that although both forms of the invention are shown as having the fuel supplied through the pilot chamber for normal burner operation it would be feasible for the fuel to be supplied by another conduit or other means for normal operation and by the conduit to the pilot chamber for pilot operation without departing from the scope of the invention.

Having thus described the invention, what is claimed and is desired to be secured by Letters Patent of the United States is:

1. A liquid fuel burner comprising a vaporizing pot, a plurality of wall members forming a pilot combustion chamber having an outlet into said pot, one of said wall members having an aperture therein for the admission of liquid fuel, one of

said wall members having an aperture therein for the admission of combustion air at a point above the maximum fuel level in said chamber, loosely dispersed elongated strips of high melting point oxidation-resistant metal of small cross section substantially filling said chamber, and said metal strips being operable to maintain continuous incandescent surface combustion thereon during pilot operation.

2. A liquid fuel burner comprising a vaporizing pot, a wall member forming with the bottom and one of the walls of said pot a pilot combustion chamber having an outlet into said pot, one of the walls of said pot having a fuel inlet aperture and an air inlet aperture into said chamber, the walls of said pot having a plurality of air inlet apertures therein, loosely dispersed elongated strips of high melting point oxidation-resistant metal of small cross section substantially filling said chamber, said metal strips being operable to maintain continuous incandescent surface combustion therein during pilot operation, and said metal strips while maintaining said continuous surface combustion being operable to ignite liquid fuel for flame combustion in said pot upon admission of fuel for normal burner operation.

3. A liquid fuel burner comprising a combustion pot, a fuel well portion opening upwardly into the bottom of said pot, means to supply liquid fuel to said fuel well portion, means to supply air for combustion to said pot and to said fuel well portion, loosely dispersed elongated strips of high melting point oxidation-resistant metal of small cross section substantially filling said fuel well portion, said metal strips being operable during pilot operation to maintain a continuous incandescent surface combustion thereon, and said surface combustion being operable to vaporize and to ignite fuel supplied for combustion in said pot.

4. A liquid fuel burner comprising a combustion pot, a fuel well portion opening upwardly into the bottom of said pot, means to supply liquid fuel to said fuel well portion, means to supply air for combustion to said pot and to said fuel well portion, a fuel vaporization member positioned in said fuel well portion and extending upward into the zone of combustion in said pot, loosely dispersed elongated strips of high melting point oxidation-resistant metal of small cross section, substantially filling the space in said fuel well portion surrounding said fuel vaporization member, said metal strips being operable during pilot operation to maintain a continuous incandescent surface combustion therein, and said fuel vaporization member being operable to vaporize fuel for combustion during normal operation.

5. A liquid fuel burner comprising a combustion pot, a fuel well portion opening upwardly into the bottom of said pot, means to supply liquid fuel to said fuel well portion, means to supply air for combustion to said pot and to said fuel well portion, a rod of highly heat conductive metal positioned in said fuel well portion and extending upward into the zone of combustion in said pot, said rod being operable when heated to vaporize fuel in said fuel well portion, an annular collar member carried by said rod and restricting the opening from said fuel well portion into said pot, loosely dispersed elongated strips of high melting point oxidation-resistant metal of small cross section substantially filling the space in said fuel well portion surrounding said rod below said collar member, said metal strips be-

ing operable during pilot operation to maintain a continuous incandescent surface combustion therein, and said rod being operable to vaporize fuel for combustion during normal operation.
